CARRIER CURRENT TELEGRAPH SYSTEM

John R. Hyneman, Chatham, N. J., assignor to
The Western Union Telegraph Company, New
York, N. Y., a corporation of New York

Application October 21, 1932, Serial No. 638,965

12 Claims. (Cl. 178—66)

This invention relates to telegraph transmitting and receiving apparatus and more particularly to a telegraph carrier current system in which code signals are transmitted in the form 5 of groups or trains of current alternations of pre-determined frequency.

The invention is applicable to land line transmission over a wide range of frequencies, but is particularly suitable to the relatively low frequency type of carrier systems, such as are commonly employed on submarine cables.

For instance on certain trans-Atlantic submarine cable routes a relatively low speed, long span cable extending across the Atlantic may be 15 connected at each end to a short section capable of operation at a higher speed. During through transmission the signal speed on the short sections is necessarily restricted to the operating speed of the longer section, although the short 20 end sections may be capable of operation at frequencies up to one hundred cycles or more. Therefore, in order to reduce the number of short sections required and provide spare channels in case of failure of a short connecting section, it 25 has been proposed to provide a carrier channel in each direction over the short sections in addition to the regular direct current channel. The current required for carrier operation over the short cable sections is relatively high, however, 30 of the magnitude of one half ampere and is not readily obtained by means of vacuum tube amplifiers.

Heretofore it has been the practice to apply the output of the carrier frequency generator 35 directly to the cable and to control the level thereof by controlling the field of the generator, or to open and close the entire output current of the generator by means of a transmitting key or relay.

A primary object of the invention is to employ 40 a gaseous conduction tube for the reception of alternating current signals.

Another object is to adapt a device normally 45 operable by half waves of one polarity only to be operated by the half waves of either polarity, thus making use of every half wave of the received alternating current signal.

Another object is to provide a carrier current 50 telegraph system in which the power output to the line may be large and which may be controlled by a keying circuit employing a relatively low current.

Another object of the invention is to provide a carrier current telegraph system in which the

received code impulses will be of uniform duration and correctly phased.

A further object is to enable the carrier frequency to be impressed upon the line in correct phase relation to the operation of the keying mechanism and more specifically to open and close the transmitting circuit at the preferred point of the cycle.

Other objects and advantages of the invention 10 will hereinafter appear.

In accordance with my invention I employ at the transmitting station, a commutator operating in synchronism with the transmitting distributor and having an output of small amplitude which controls the discharge from gaseous 15 conduction tubes of a type which are capable of passing a relatively large amount of current. The characteristics of the gaseous tubes are such that they normally interpose a high resistance in the circuit in which they are connected, this 20 resistance being broken down by a relatively small current in the auxiliary or control circuit, the tube then being capable of passing a large amount of current.

A type of tube which I have found particularly satisfactory for this purpose is described in an article by Dr. Albert W. Hull, entitled "Hot Cathode Thyatrons" and published in the General Electric Review, Vol. 32, #4, of April, 1929, at page 213. This type of tube is in effect an 30 electrostatically controlled arc rectifier and briefly consists of a gas filled envelope containing an electron emitting cathode, a surrounding grid and an anode, the geometry of the tube, nature 35 and pressure of the gas and electron emissivity of the cathode being such that with the proper positive potential applied to the anode, the grid will interpose a high starting resistance to the tube but if the potential of the grid is raised to a critical value by a feeble current, the tube 40 will break down and due to the arc discharge then occurring, will allow a large amount of current to flow from the anode to the cathode.

The tube is unlike the ordinary three electrode vacuum tube or audion in that as soon as the plate 45 current starts, the grid has no further influence on the plate current and the discharge can only be stopped by removing or reducing the plate voltage.

Two such devices are arranged to operate as an 50 inverter their input circuit being coupled to the commutator and transmitting distributor in such manner that the gaseous conduction devices operate alternately during reversals of current. The output of the gaseous conduction devices is ap-

plied to a transformer, the secondary winding of which is connected to a line through a filter which serves to eliminate the higher harmonic frequencies normally present in the square top wave 5 from the commutator.

At the receiving station the signals are rectified or detected and applied to the grid of a single gaseous conduction tube having a rotary distributor connected in the output circuit whereby, as 10 the distributor brush rotates in synchronism with the transmitted signals, the output circuit of the tube will be interrupted between each signal and the signal will be regenerated so that substantially perfect signals will be supplied to the receiving 15 printer.

The system may be either start-stop or multiplex and in the latter case the printer circuit may be arranged so that the printers associated with each alternate channel will operate on the received oscillations as marking signals and those associated with the intermediate channels will operate on the received oscillations as spacing signals.

In order that the invention may be more fully understood reference will be had to the accompanying drawing in which:

Figure 1 is a circuit diagram showing the transmitting apparatus for a carrier current channel embodying my invention, in this case adapted for handling a regular multiplex printing telegraph 30 circuit, and

Figure 2 shows diagrammatically the associated receiving system.

Figure 3 is a circuit diagram of a modified receiving arrangement.

The transmitting apparatus shown in Figure 1 comprises a suitable transmitter 10 which may be either a manually controlled transmitter, or a tape controlled transmitter, such as is described in 40 patent to G. R. Benjamin, No. 1,298,440, granted March 25, 1919, and entitled Automatic transmitter. The transmitter is diagrammatically illustrated as comprising a plurality of stationary 45 grounded contacts 11 and a group of movable contacts numbered 1 to 5. The contacts 1 to 5 are connected to the correspondingly numbered segments of ring 12, of a multiplex distributor TD. A solid ring 13 is associated with the segmented ring 12. The distributor preferably has a second 50 set of rings comprising a solid ring 14 and a segmented ring 15, the number of segments of the latter ring being an even multiple of the number of segments of the transmitting ring 12. The alternate segments of ring 15 are strapped together and connected to one polarity of the battery 16 and the remaining segments are connected to the opposite pole of the battery. The midpoint of the battery is grounded. Brushes B1 and B2 55 traverse the rings 12, 13 and 14, 15 respectively, in unison. Solid rings 13 and 14 are connected respectively to the opposite ends of the primary winding 17 of a transformer 18.

In transmitting a single character code combination, the contacts 1 to 5 of the transmitter 10 are set up in accordance with the combination, thereby grounding pre-determined segments of ring 12. Upon engagement of the brush B1 with the grounded segments current reversals occur in the winding 17 and during the engagement of the brush with the ungrounded segments, the circuit of the winding 17 is open.

The current reversals produced in the windings of the transformer 18 may be of low amplitude and therefore readily interrupted on the segments 75 of ring 12. In order to increase the output of the

transmitter, I employ an inverter comprising two gaseous conduction tubes 21 and 22 which may be of the type described in the aforesaid article by Hull type or other type having similar characteristics thereto, each tube having a positive electrode or anode 23, an electron emitting cathode 24, either of the directly or indirectly heated type, and a grid 25, enclosed within a gas filled envelope. The input and output circuit of the tubes 21 and 22 are arranged so that upon the application of a critical potential to the grid of one of the tubes, a discharge is initiated therethrough, which causes the discharge to cease in the other tube. Thus by alternately applying a starting potential to the grids of the two tubes, they may be caused to operate alternately. The cathodes 24 of the two tubes are connected together and to the negative terminal of a battery or other source of potential 26. The anodes 23 are connected through resistances R₁ and R₂ to the opposite terminals of the primary winding 27 of an output transformer 28 and are directly bridged by a condenser 29. The midpoint of the winding 27 is connected to the positive terminal of the battery 26. The grids 25 of the gaseous discharge tubes are connected to the opposite terminals of the secondary winding 30 of the transformer 18, the midpoint of which is joined through a stabilizing battery 31 to the cathodes of the tubes. The secondary winding 32 of the output transformer is connected to the 20 outgoing line circuit L through a suitable transmitting filter 33.

The operation of the inverter is as follows:

With segment 1 of ring 12 grounded, as the brush B1 passes thereover, current reversals are 35 produced in the winding of the transformer 18 and the grids of the tubes 21 and 22 are alternately rendered positive. Assuming that on the first half cycle the grid of tube 21 is made positive, the internal resistance of this tube will be 40 decreased and a discharge initiated therethrough, the current flowing from the positive terminal of the battery 26 through the lower half of the winding 27 of the output transformer and resistance R₁ to the anode of tube 21, and thence 45 from the cathode thereof back to the battery 26. A current is thus induced in the line circuit L, through the filter 33, in a definite direction. The tube 21 continues to operate as long as positive potential is applied to the anode thereof, independently of the grid 25 and until the beginning of the next current reversal through the transformer 18, at which time the positive charge is removed from the grid of tube 21 and a similar 50 positive charge applied to the grid of tube 22. 55 Tube 22 therefore starts to operate, permitting current to flow from the positive terminal of the battery 26 through the upper half of the winding 27 of transformer 28 in the opposite direction. The condenser 29 which was previously charged from the tube 21, is now subject to a displacement current in the opposite direction and therefore discharges in such a direction as to momentarily reduce the voltage in the plate circuit of the tube 21 sufficiently to permit the 60 tube to become deionized and interrupt the flow of current therethrough. The tube 22 continues to operate, inducing a current in the line circuit L in the reverse direction from that induced due to the operation of the tube 21. Alternations 70 are thus sent over the line circuit L at a frequency determined by the rate of passage of the brush B2 over the segments of ring 15.

If the second intelligence signal, controlled through contact 1 of the transmitter, is of mark- 75

ing character, a second train of oscillations will be transmitted over the line circuit L, the number of reversals or cycles comprising the marking signal depending of course upon the number of 5 segments of ring 15 traversed by the brush B2 while the brush B1 is passing over a segment of ring 12.

Assuming the second intelligence signal to be spacing, the transmitter contact 2 will remain 10 open and the grids of both tubes 21 and 22 will remain below the critical starting potential under the influence of the stabilizing battery 31. The particular tube operating at the end of the preceding marking signal will continue to operate 15 during the spacing period, but since the discharge is of a continuous nature, no current will be induced in the line circuit L. Also since each segment of ring 12 encompasses an even number of segments of ring 15 the initial reversal will always 20 be of the opposite polarity from the terminating reversal of the last marking segment so that the idle tube will always be effective to transmit the initial half wave to line. In cases where the current requirements can be met by the distributor alone without the inverter tubes, an uneven 25 number of half waves may be used for a signal.

In the output of the transformer 28 a transmitting filter 33 of well known type should be employed for the purpose of purifying the wave to prevent interference to other channels operating at other frequencies on the same or contiguous cables. Therefore, each marking signal is transmitted over the line circuit as a train of oscillations and the spacing signals as no current intervals.

It will be noted that due to the positive drive connection between the brushes B1 and B2 (both being mounted on the same shaft) that each 40 group of oscillations produced by grounding one of the segments of ring 12 contains a uniform number of alternations (ten each in the embodiment shown), the oscillations being in phase with the transmitted signals, that is, the circuit being opened and closed only at the time the oscillations pass through the zero-point. Each marking signal, therefore, consists of a uniform number of whole impulses or half cycles. This latter 45 feature is important in carrier telegraph systems since when the circuit is opened and closed indiscriminately and at other than the zero point, a severe transient is transmitted into the cable which may interfere with the direct current receiving apparatus operating on the same cable. 50 Further, at the receiving end the mutilated half cycles at the start and finish of the signal may be received imperfectly thus causing a fortuitous shortening and lengthening of the signal.

One form of receiving apparatus is shown in 55 Figure 2 and includes the receiving transformer 34, a receiving filter 35, and an amplifier 36. The amplifier 36 is coupled through a transformer 37 to the input of a full wave rectifier comprising two vacuum tubes 38 and 39 having their grids connected to the opposite terminals of the secondary winding of the transformer 37 and the cathodes connected through the biasing battery 40 to the mid-point of the secondary winding of the transformer. Although the thermionic rectifiers are illustrated here other types also will serve satisfactorily. The plate circuits of the tubes 38 and 39 are coupled to the input circuit of a gaseous conduction tube 41 through the impedance R3. The grid of the tube 41 is normally maintained 60 below the critical starting potential of

the tube by the stabilizing battery 42. Whenever a discharge occurs in either of the tubes 38 or 39 a positive potential is applied to the grid 43 due to the potential drop across the impedance R3.

The anode 44 of the tube 41 is joined to the solid ring 45 of a receiving distributor RD and the cathode 46 is connected through the battery 47 to one terminal of the windings of the selecting magnets 48 to 52 to a multiplex printer, the opposite terminals of these magnets being connected to the segments 1 to 5 of the receiving ring 53 of the distributor. The brush B3 passes across the segments 1 to 5 in substantial synchronism with the transmitted groups of oscillations.

As the brush B3 engages segment 1, during the reception of the first train of oscillations, the grid of the tube 41 will be raised above the critical starting potential through the action of the rectifier, irrespective of whether the particular half cycle being received at the time is of positive or negative polarity. Consequently the tube 41 will immediately start to operate, the circuit being completed from the anode 44, through ring 45, brush B3, segment 1, selecting magnet 48 and 20 battery 47 to the cathode 46. As the brush passes on to the dead segment following segment 1, the plate circuit of the tube 41 is interrupted and the discharge through the tube ceases. As the brush now passes on to segment 2, if a marking signal 30 is being received over the line a second discharge starts through the tube 41 thereby operating the selecting magnet 49. However, if a spacing signal or no current interval occurs at this time tube 41 remains unoperated and the selecting 35 magnet unenergized. The discharge through the tube 41 is interrupted after each signal and before the reception of the succeeding signal train as the brush B3 passes over the intermediate dead 40 segments.

The live segments of the receiving distributor are of such width as to correspond to the central portion only of each train of received oscillations thereby insuring that the received signals will be of sufficient strength to initiate a discharge 45 through the tube 41 as the brush engages the live segments of the distributor.

By the use of the three element detector the alternating current signal is converted into a direct current signal quite similar in its characteristics to the ordinary direct current signal, thus permitting the employment from this point onward of standard cable practices, as for instance in amplifying and shaping, in receiving instruments, and in synchronizing methods. The 50 full wave detector makes the receiving equipment independent of chance alterations in the polarities connected to the rings of the sending distributor and so is preferable to a single wave 55 device.

The rectifier also adapts the system for transmission by the Morse or other similar two element code. The Morse key in conjunction with one of the well known methods for opening and closing the circuit at a no-current period should be substituted in place of the transmitter 10 and distributor rings 12 and 13. At the receiving end the single gaseous conduction tube but without the distributor RD will not interrupt the circuit during spacing intervals. Therefore the single 60 tube should be replaced by a pair of tubes connected in inverter fashion as shown in Fig. 3.

The plate circuits of tubes 38, 39 are coupled to the input circuit of two gaseous conduction tubes 54 and 55 through impedance R3. A filter 75

or shaping device F is inserted in the output circuits of tubes 38 and 39 to remove the A. C. component of the rectified signals. Tube 54 has its grid normally biased positive by battery 56 and tube 55 has its grid biased negative by battery 57. A battery 58 is arranged to normally oppose the plate battery 59 of tubes 38, 39. When no signals are received over the line the points 60 and 61 of the circuit are at zero potential, due to the opposing effect of batteries 58 and 59. Consequently, tube 54 is operated (due to its positive grid) and tube 55 is unoperated. Whenever a train of oscillations is received, causing a flow of direct current across the impedance R3, the point 60 becomes negative and the point 61 positive, relative to the cathodes of the tubes 54 and 55 thereby overcoming the biasing effect of the batteries 56 and 57 and reversing the charges on the grids of these tubes. The tube 55 is thus caused to operate. The tubes are connected in inverter arrangement through the resistance R4 and condenser C, whereby the starting of the discharge through one tube interrupts the discharge through the other. Consequently, the tube 55 is caused to operate during the reception of a signal train, that is during the reception of a dot or dash of Morse code, and the tube 54 is caused to operate during a spacing signal. A sounder S, operated by relay 56 included in the output circuits of tubes 54 and 55, responds to the Morse signals.

It can be seen that if the rectifier tubes 38, 39 were not provided the inverter tubes would respond in rapid succession to the alternate half waves of the marking signals instead of responding alternately to the marking and spacing signals respectively.

Inasmuch as the gaseous conduction tubes of the type mentioned of moderate size are capable of passing large currents, of several amperes, under the control of feeble currents, the present system is particularly adaptable for carrier current telegraph systems which require the transmission of large amplitudes.

While I have shown the invention with particular reference to a multiplex telegraph system it is to be understood that it is equally applicable to a start-stop system. In this case also means should be provided to start the transmitting distributor at the zero point of each alternation produced by the commutator ring 15.

It is understood that the system described can be superimposed on a submarine cable or other signaling circuit carrying a regular direct current transmission channel, and that a number of such systems each employing a separate frequency may be operated simultaneously over said circuit.

It is obvious, of course, that the invention may be embodied in various other forms without departing from the invention and, therefore, I do not desire to be limited to the exact details shown and described but contemplate all variations as coming within the scope of the appended claims.

What I claim is:

1. In a carrier current telegraph system, a source of signals, said signals comprising groups of current oscillations, a receiving apparatus for said signals comprising an electrostatically controlled gaseous conduction tube and means for initiating a discharge through said tube in response to either a positive or negative half cycle of said received oscillations.

2. In a carrier current telegraph system, a source of signals, said signals comprising groups

of current oscillations, a receiving apparatus for said signals comprising an electrostatically controlled gaseous conduction tube and a full wave detector responsive to received oscillations for applying a starting condition to said discharge tube in response to both the positive and negative half cycles of said received oscillations.

3. In a carrier current telegraph system, a source of signals, said signals comprising groups of current oscillations, a multiplex distributor on which said signals are received, a gaseous conduction device having an input and output circuit, means for completing said output circuit through said distributor in synchronism with received oscillation groups and means for applying a starting potential to the input circuit in response to both positive and negative half cycles of said received oscillations.

4. In a carrier current telegraph system, a source of signals, said signals comprising groups of current oscillations, a receiving apparatus comprising a rectifier for said received oscillations, a gaseous conduction tube controlled by said rectified current, a synchronous distributor in the output circuit of said tube and a receiving instrument controlled by said distributor.

5. In a carrier current telegraph system, a source of signals comprising groups of current oscillations, a full wave rectifier for said oscillations adapted to produce uni-directional impulses, a trigger device subject to said uni-directional impulses and adapted to be started into operation thereby, and means operating synchronously with said signals for interrupting the operation of said device.

6. In a carrier current telegraph system, means for transmitting groups of current oscillations, each group comprising a whole number of impulses, a receiving apparatus therefor comprising a full wave rectifier and a gaseous conduction relay adapted to be started into operation by said rectified oscillations, and means independent of said oscillations for interrupting the operation of said relay.

7. In a carrier current telegraph system, a transmitting apparatus comprising a pair of gaseous conduction tubes disposed in push-pull relation, means for producing discharges in said tubes alternately, keying means for starting and stopping said alternate operation of said tubes in accordance with a predetermined code, and means for effecting said starting and stopping at a frequency which is an even divisor of the frequency of said alternations.

8. In a carrier current telegraph system, a transmitting apparatus comprising an alternator, a distributor operating in synchronism therewith and containing segments, each of which subtends a uniform whole number greater than one of half cycles, and means for completing signal circuits serially through said alternator and distributor in accordance with a prearranged code.

9. In a carrier current telegraph system, a transmitting apparatus comprising an alternating current commutator, a transmitting distributor operating in synchronism therewith, said distributor serving to make and break the circuit through said commutator in accordance with a prearranged code and in definite timed relation to each alternation produced by said commutator and a transmitting apparatus controlled by the alternations produced in said circuit.

10. A carrier current telegraph system comprising an arc discharge path for each polarity of current, an input circuit for each discharge path,

- a source of current alternations in said input circuits for producing discharges alternately through said paths, a keying device for said source of alternations, means for opening and closing said keying device as said oscillations pass through a zero point, a line circuit and means for completing the output of said tubes to said line circuit.
11. In a carrier current telegraph system, a source of carrier current telegraph signals comprising two different line conditions, a pair of electrostatically controlled gaseous conduction tubes having control electrodes, said electrodes being so biased that one tube responds to one line condition and the other tube responds to the

other line condition and receiving means in the output circuits of said tubes.

12. In a carrier current system, a source of telegraph signals comprising groups of current oscillations, a pair of gaseous conduction tubes, one of said tubes being responsive to current oscillations to produce a discharge therethrough, and the other being responsive to cessation of oscillations to produce a discharge therethrough, whereby said tubes operate alternately, a receiving instrument and means including the output circuit of said tubes for applying steady current conditions to said receiving instrument in response to said received oscillations.
